Primary Examiner — Michael C Stout*Assistant Examiner* — Rani J Abdallah(74) *Attorney, Agent, or Firm* — Jacob M. Ward; Ward Law Office LLC(57) **CLAIM**

The ornamental design for a trash can bottom lift handle as shown and described.

DESCRIPTION

FIG. 1 is a top front perspective view of a trash can bottom lift handle;

FIG. 2 is a bottom rear perspective view thereof;

FIG. 3 is a front elevational view thereof;

FIG. 4 is a rear elevational view thereof;

FIG. 5 is a right-side elevational view thereof, a left-side elevational view is not shown because it is a mirror image to the right-side elevational view;

FIG. 6 is a top plan view thereof; and,

FIG. 7 is a bottom plan view thereof.

The broken lines shown in the drawings form no part of the claimed design.

1 Claim, 7 Drawing Sheets# US D1,097,431 S
